(No Model.)

L. ARMSTRONG.
BENCH VISE.

No. 433,973.

Patented Aug. 12, 1890.

UNITED STATES PATENT OFFICE.

LEWIS ARMSTRONG, OF WORCESTER, MASSACHUSETTS.

BENCH-VISE.

SPECIFICATION forming part of Letters Patent No. 433,973, dated August 12, 1890.

Application filed July 14, 1887. Serial No. 244,334. (No model.)

To all whom it may concern:

Be it known that I, LEWIS ARMSTRONG, a citizen of the United States, residing at Worcester, in the county of Worcester and State of Massachusetts, have invented a new and useful Improvement in Bench-Vises, of which the following is a specification, reference being had to the accompanying drawings, representing a bench-vise embodying my invention, and in which—

Figure 1 is a longitudinal sectional view on line X X, Fig. 3. Fig. 2 is a transverse sectional view on line Y Y, Fig. 1. Fig. 3 is a view of the vise removed from the bench. Fig. 4 is a top view of the movable jaw and connected operating mechanism. Fig. 5 is a sectional view of the end of the lever H. Fig. 6 is an end view of the lever H with the handle K removed. Fig. 7 is a detached view of the retaining-pawls.

Similar letters refer to similar parts in the several views.

A A denote the bench, to which the fixed jaw is attached.

B is the fixed jaw attached to a plate B', which extends beneath the bench A, to which it is fastened by bolts passing through the lugs a a, Fig. 3. The plate B' is provided with ways C C to receive the bars D D of the movable jaw E. The bars D are retained in position by means of the plates C', Fig. 1. In the central portion of the plate B' and between the ways C C is a rack F, provided with lugs F' F', which pass through mortises in the plate to receive the keys F², by which the rack F is held in position against the under side of the plate B'. The bars D D are also provided with the downwardly-extending lugs D', supporting the lever H upon the pivot G. The lever H has the

toothed arm H', having an oscillating motion about the pivot G. To the outer end of the bars D D, I attach the curved ratchet-bar I, having a slot I', through which the free end of the lever H passes. Upon the lever H are pivoted the pawls J, having a lever J', extending through the slot I' beneath the handle K. When the handle K is raised to its highest position, as seen in Fig. 1, the toothed arm H' is carried over far enough to clear the rack and permit the movable jaw to be drawn out to receive the work between the movable and

fixed jaws. The handle K is then carried downward in the direction of the arrow 1, Fig. 1, causing the teeth in the arm H' to engage the rack F, which, being held in a fixed position, acts as a fulcrum and carries the sliding bars inward, bringing the jaws of the vise together and firmly clamping the work between them, the pawls J J sliding over the teeth of the ratchet-bar I and retaining the lever H in its lowest position. When the work is to be released, the pawls J J are disengaged from the curved ratchet-bar by raising the lever J' with the finger as the handle K is seized by the hand. The lever H is raised, moving the movable jaw outward and releasing the work.

The body of the lever H is made of wood preferably, as a more yielding material whose elasticity allows the lever to be sprung slightly to compensate for the coarseness of the teeth c on the ratchet-bar I, and is attached to the arm H' by means of the prongs d d and bolt e. The outer end of the wooden bar enters a metallic shell L. (Shown in section in Fig. 5 and in end view in Fig. 6.) The handle K has a shank K', with a pin f, which passes through the slots g g in the shell L, and by a quarter-turn of the handle serves to retain the handle in place and allow it to be readily removed to prevent the vise from being used or to clear the space in front of the jaws B and E.

A light spring h is employed to sustain the weight of the lever H and maintain it in its highest position, so that the teeth in the arm H' will clear the teeth of the rack F except when the lever H is held down by the pawls J engaging the teeth of the curved ratchet-bar I.

What I claim as my invention, and desire to secure by Letters Patent, is—

1. The combination, substantially as hereinbefore set forth, with the stationary jaw provided with a rack attached to said stationary jaw, of a movable jaw, downwardly-projecting lugs attached to said movable jaw and inclosing between them the fixed rack, a lever pivoted in said lugs and provided with a short arm with its end concentric with the axis of said lever and provided with teeth adapted to engage said rack as the lever is depressed and to clear said rack as the lever is raised to its highest position, substantially as and for the purpose specified.

2. The combination of the fixed jaw, a plate formed integrally with the fixed jaw and extending beneath the bench and provided with the mortises to receive the lugs of a fixed rack, 5 a fixed rack provided with lugs entering said mortises, a movable jaw having bars D D formed integrally therewith and sliding in ways in the plate of said fixed jaw, lugs projecting downwardly from said bars and in-
10 closing said rack, a lever pivoted in said lugs and having a short arm concentric with the axis of the lever and provided with teeth ar-

ranged to engage said rack as the lever is de-
pressed and move the movable jaw toward
the fixed jaw, and also to clear said rack as 15
the lever is raised to its highest position to
allow said movable jaw to be moved inde-
pendently of the engagement with said rack,
substantially as and for the purpose specified.

LEWIS ARMSTRONG.
